UNITED STATES PATENT OFFICE

JESSE VANCE MATTESON, JR., OF SANTA ROSA, CALIFORNIA

METHOD OF AND APPARATUS FOR USE IN CASTING DENTAL MODELS

Application filed March 19, 1928. Serial No. 262,949.

This invention relates to a method and apparatus for use in conjunction with the casting of the plaster models used in orthodontic dentistry, and it relates more particularly to a 5 plaster model levelling set, and the method of use of the same by means of which the plaster models may be poured in such manner that the base and tops of the models are parallel and smooth, and the occlusal line of the teeth 10 lies in a plane parallel to the top and bottom of the two models, and midway between them. The model of the present invention eliminates all trimming and adjusting of the top, bottom, or occlusal planes, and results in all 15 models being of the same weight and proportion. Heretofore, these results were accomplished by use of a rule and hand plane. Under the method of my invention the plane is necessary only on peripheral margins.

20 The accompanying drawing illustrates apparatus by means of which the above described results may be secured.

In the drawing,

Fig. 1 is a plan view, and

25 Fig. 2 is an end elevation of an instrument adapted to initially support and level the mandibular impressions.

Figs. 3 and 4 are, respectively an end elevation and a plan view of an instrument 30 adapted to receive the mandibular impressions from the structure of Figs. 1 and 2, and to support the same after the removal of the latter, and

35 Figs. 5 and 6 are, respectively, an end elevation and a plan view of a mechanism adapted to engage and support the maxillary model, as hereinafter described, and

40 Figs. 7, 8, 9 and 10 are elevations showing various stages in the use of the apparatus as more particularly, hereinafter described.

The structure of Figs. 1 and 2 comprises a 45 plurality of vertically disposed pins 5, having pointed upper ends, which pins carry perforate blocks 6. These blocks, in turn, are formed intermediate their length to constitute set screws 7, by which they may be bound in adjusted position along horizontal arms 8. The inner ends of these arms are provided with eyes through which a lock bolt 9 passes.

50 A thumb nut 10, on the lock bolt, provides

means for binding the several arms 8 against movement with respect to each other. In use, the structure is supported with the pointed ends of the pins upward, and it is clear that the position of these pins over a horizontal area may be varied over somewhat wide ranges, by adjustment of the blocks 6 along the arms 8, and by the movement of the arms themselves upon the pivot provided by the latch bolt 9.

55 The structure of Figs. 3 and 4 is used in conjunction with the structure of Figs. 1 and 2. The structure of Figs. 3 and 4 comprises a Y-shaped or triangular tripod 14, which is adapted to be supported in a horizontal plane by the legs or supporting screws 15. At their outer ends these screws are provided with knurled heads 16, by which they may be turned. Lock nuts 17 serve to bind the screws against movement, after they have been adjusted. The structure of Figs. 5 and 6 comprises an open frame 17, which is supported upon screws 18, which constitute legs for said frame. Lock nuts 19 are mounted upon the screws 18 and knurled heads 20 are disposed upon said screws. The frame 17 carries upstanding ears 21, in which set pins 22 are threaded, said pins having pointed inner ends 22^a to adapt them to engage the maxillary model in the manner hereinafter set forth.

70 The method of use of the levelling mechanism described is as follows:

75 The lower or mandibular impression is first set upon the upper ends of the pins 5. Thus, the height of the mandibular impression from the base or table, (the surface of which is indicated at 6^a), is determined. Then the tripod of Figs. 2 and 3 is set in position over the mandibular impression, and the tripod or Y 14 is waxed to said mandibular impression. (See 80 Fig. 9). Then the structure of Figs. 1 and 2 is removed, leaving the mandibular impression suspended from the Y 14, but at the same height from the table that it occupied when it was supported on the pins 5.

85 The mandibular impression which has its imprint side next to the table is then bodily inverted along with the tripod and filled with a creamy mix of plaster of Paris, and is then turned back into this former position upon 90

the table over a pile of creamy plaster of Paris P, as is illustrated in Fig. 8.

After the plaster hardens, the tripod is removed, and the wax of the mandibular impression is softened by heat, and removed from the plaster, thus leaving the plaster model of the lower teeth complete upon the table, except for peripheral trimming. The upper or maxillary impression is next filled with plaster to its capacity. After the plaster has set, the wax is removed, and there is left a plaster model in detail of the upper teeth. This upper plaster model is then placed upon the mandibular model on the table in such position as to occlude or bite with the same. Then the structure of Figs. 5 and 6 is placed about the mandibular model, and its set pins 22 are turned to cause their pointed inner ends to engage with the maxillary model. At this time, adjustment of the supporting screws 15 raises or lowers frame 17, to bring it to the proper height. The position of the parts at the time that the set pins 22 are caused to engage the maxillary model, is illustrated in Fig. 9. Then the lower model is removed, leaving the upper model suspended by the frame 17, and its associated parts. This frame and the maxillary model are then inverted on to a pile of creamy plaster of Paris (see Fig. 10), thus completing the formation of the maxillary model. Upon setting, the models are placed in occlusion or bite, and are trimmed peripherally to secure the desired appearance.

It will be seen that by the use of the simple elements herein shown and described, I am able to produce dental plaster casts in such a way that the tedious and time consuming measures heretofore resorted to in the trimming up of the plaster models, are completely avoided.

It is to be understood that the invention is not limited to the precise construction set forth, but that it includes within its purview whatever changes fairly come within either the terms or the spirit of the appended claims.

Having described my invention, what I claim is:

1. A structure of the character described, comprising a frame open at the top adapted to embrace a maxillary model, having supporting legs for holding the frame in a substantially horizontal position, and members movable toward and from the interior of the frame in a substantially horizontal plane, adapted to engage and bind a maxillary model and means for vertically adjusting the frame upon its legs.

2. A structure of the character described, comprising an open frame, screws adjustable therethrough, constituting legs therefor for supporting said frame at varying heights, and threaded set pins carried by said frame having pointed inner ends movable toward

and from the interior of said frame, as and for the purposes set forth.

3. The herein described method, which consists of initially supporting a mandibular impression upon an upstanding support, disposing an overhanging support above said impression and securing the impression to the last named support, and thereafter removing the upstanding support, and thereafter inverting the mandibular impression upon a pile of soft plaster.

4. The herein described method, which consists of initially supporting a wax impression, of one set of a person's teeth above a plane surface and upon an upstanding support, disposing an overhanging support above said impression and securing the impression to the last named support, then removing the upstanding support, then bodily inverting the impression upon a pile of soft plaster upon said plane surface, and then removing the material of the impression to leave a model of the teeth in plaster upon said plane surface at a height determined by the initial setting of the upstanding support.

5. A method as described in claim 4, in combination with positioning a wax model of the other set of the person's teeth upon said plaster model in occlusion, engaging a support which is, in turn, supported from said plane surface with the last named wax model, and then inverting the same upon a pile of soft plaster supported on the said plane surface.

In testimony whereof I affix my signature.
